BULLET LUBRICATOR

Lucius E. Wadman, Mill Valley, and Frederick J. Gomes, Tiburon, Calif.

Application February 10, 1947, Serial No. 727,506

4 Claims. (Cl. 86—19)

1

This invention relates to a device for sizing and lubricating a bullet.

Bullets for use in the hand loading of ammunition are usually cast in a mold. Before it can be positioned in a cartridge, it must first be sized. This has been accomplished heretofore by forcing the bullet through a suitable die so that when the bullet issues from the die it is of the correct size to fit the rifle in which it is to be used. The bullet must also be lubricated so that it will fit readily into the chamber of the rifle and so that it will carry a lubricant with it down the rifle barrel. In some instances, the bullet, after having been sized, is lubricated by hand. Bullet sizing devices have been attempted heretofore in which the lubricant is supplied under pressure to the die so that the lubricant is applied to the bullet as it undergoes sizing, the pressure application continuing to such an extent, even after the bullet had passed through the sizing die that the flow of lubricant continues. As a result, considerable wastage ensues, and the device becomes covered with the lubricant, particularly if the lubricant supply pressure was maintained sufficiently high to ensure an adequate supply to the die. If the lubricant supply pressure is maintained relatively low to reduce waste, the bullets are generally under-lubricated.

The device of the present invention embodies a bullet sizing die which is supplied with a lubricant under pressure. In addition, the device includes means for controlling the supply of lubricant so that application of the lubricant occurs only when a bullet is in position in the die for lubrication, the flow of lubricant being cut off positively during the initial portion and the final portion of the traverse of the bullet through the die. In this way, the lubricant is conserved, any excess lubricant under pressure being drained off and collected for re-use. The device of the present invention thus ensures that an adequate and uniform quantity of lubricant is applied to each bullet with an entire absence or at least a minimum of lubricant wastage.

It is the generally broad object of the present invention to provide an improved bullet sizer and lubricator.

Another object of the present invention is to provide a novel bullet sizer and lubricator.

A further object of the present invention is to provide a bullet sizer and lubricator in which the supply of lubricant to a bullet undergoing sizing is controlled to the end that the lubricant is applied to the bullet only during an intermediate portion of the sizing operation so that an ade-

2

quate and uniform amount of lubricant is applied to each bullet sized.

The invention includes other objects and features of advantage, some of which, together with the foregoing, will appear hereinafter wherein the present preferred form of bullet sizer and lubricator of our invention is disclosed.

In the drawings accompanying and forming a part hereof, Figure 1 is a plan view of the bullet sizer and lubricator of this invention.

Figure 2 is a side elevation of the sizer and lubricator.

Figure 3 is an end elevation of the sizer and lubricator.

Figures 4, 5 and 6 are each side elevations, partly in section, of a portion of the bullet sizer and lubricator illustrating successive positions of various elements of the sizer and lubricator.

Figure 7 is a side elevation partly in section of a modified form of sizer and lubricator.

Referring to the drawings, the device includes a suitable base 7 adapted to be secured to a fixed support. Secured to the base 7 by studs 8 is a U-shaped frame generally indicated by numeral 9 and having spaced legs 11 and 12, the latter being positioned in supporting engagement with the base plate 7. Mounted in the leg 12 is a removable bullet sizing die generally indicated by numeral 14. The die is removably mounted in leg 12 by screw thread 13 so that various dies can be inserted and bullets of different diameters sized in the device.

Slidably mounted in leg 11 of the frame 9 is a plunger 15 having an end 16 formed to engage the generally ogival end of a bullet and to force the bullet through the bullet sizing die 14, the plunger being movable along the longitudinal axis of the sizing die. To move the plunger 15, a handle 17 is provided, the latter being shortened

in the drawings for convenience of illustration. A clevis 18 is mounted upon the end of plunger 15 and a pin 19 is extended through the clevis and through handle 17. The handle is supported intermediate its ends by a link 21, one end of which is mounted upon a pin 22 in a suitable recess in the frame member 9 while the other end is connected by a pin 23 to the handle. Lowering of handle 17 moves the plunger 15 toward and into the die to force a bullet through the die for sizing; lifting of the handle retracts the plunger.

To supply lubricant to a bullet undergoing sizing, we provide a lubricating channel 26 about the exterior of the bullet sizing die so that a lubricant under pressure can be applied to grease grooves 27 formed in the surface of the bullet 28.

within the die through a plurality of spaced apertures 29.

Means are provided for supplying lubricant to the lubricating channel 26 including a lubricant reservoir generally indicated by numeral 31 and comprising a cylindrical vessel 32 screwed into fitting 33, the latter being carried in a street-ell or elbow 34 which is in turn secured to a nipple 36 on the side of frame 9. Within the vessel 32 is provided a movable plunger 37 carried on a spring 38, the spring being in turn carried upon a piston 39 mounted upon the end of threaded rod 41 which extends through threaded casting end 42, a handle 43 being provided on the end of the rod.

The construction just described comprises a well known form of grease gun which, upon being filled with lubricant and upon rotation of the threaded rod 41 by handle 43, supplies a lubricant under pressure through the nipple 36.

Within leg 12 of frame 9 is provided a first passage 46 leading in from the nipple 36 through the frame to a second passage 47 formed in plug 50 and in the frame and leading to the lubricating channel 26 in the bullet sizing die. A piston 49 is slidably mounted in the second passage 47 to cut off the supply of lubricant from passage 46 and to force the lubricant in the second passage 47 into channel 26 and onto the grooves in a bullet.

In accordance with this invention, means are provided for controlling the supply of lubricant and for coordinating this with the positioning of a bullet in the die so that the lubricant is only supplied to the bullet to lubricate the latter when it is in position in the die. To this end, a portion of the second passage 47 is preferably positioned at a suitable angle to the longitudinal axis of the die so that a valve member 51 can be moved into position to control the supply of lubricant to the die. The valve member 51 is adjustably supported on a rod 54 which is slidably guided by leg 11 and is supported by a clevis 52 and a pin 53 from handle 17. Intermediate its ends, the valve member 51 includes a passage 56 which, when suitably positioned, permits the lubricant to flow through the second passage. To move the plunger 49 and to coordinate its movement with that of the valve member 51 and the plunger 15, a clevis 61 is mounted upon an end of the piston and a link 62 is extended between this clevis and arm 63 on a bell crank 64 mounted on post 65 on base 7. The other arm 67 of the bell crank is connected by adjustable link 68 to handle 17.

To permit release of pressure on the lubricant remaining in that portion of the second passage 47 which extends between the valve member 51 and the channel 26, a bleed-off conduit 71 is provided in the valve member 51 leading to the bottom of the valve member which extends below base 7 so that the lubricant can be drained off and collected.

In operation, a lubricant of suitable grade and quality is placed in the lubricant supply vessel 32 and handle 43 is turned to force the lubricant into second passage 47 under a relatively low pressure. A bullet is then positioned between the die and the plunger 16. Upon lowering handle 17, the bullet is forced into the die. At the same time, valve member 51 is lowered from the pressure relieving position shown in Figure 4. The travel of the valve member is substantially parallel to that of the plunger and its rate of travel is such that by the time a bullet is in position in the die, the valve member has moved

down to cut off the flow of lubricant through passage 47 and into a position intermediate those of Figures 4 and 5. Continued movement of the handle 17 moves piston 49 into position, first to cut off the flow of lubricant from passage 46 into passage 47 and then to place a higher pressure on the lubricant in passage 47. By this time, valve member 51 is in such a position that passage 56 is in position to pass the lubricant on into the lubricating channel 26 as in Figure 5. Continued depression of handle 17 results in the bullet being forced on through the die; due to the linkage connection and the rate of movement of bell crank 64, the movement of the piston 49 is discontinued. However, valve member 51 continues to move with handle 17 and to cut off the supply of lubricant as the bullet is moved past channel 26 as will be seen if one compares Figures 5 and 6. When the bullet has been forced through the die, handle 17 is raised to return the plunger, the valve member and piston to their starting positions (Figure 4) wherein conduit 71 is positioned to relieve the pressure. The bullet is not forced completely through the die, the handle being returned to its raised position and another bullet inserted to force the bullet in the die out of position, the second bullet being forced through the die, sized and lubricated.

In Figure 7 we have shown a modified form of device wherein rod 54 is utilized as the lubricant cut-off and pressure applicator. To this end rod 54 is provided with a plunger portion 91 movable through a chamber 72, the latter being supplied with lubricant by lubricant reservoir 31. Base 9 includes two passages 73 and 74, one leading to the bullet die 14 and the other to an excess lubricant passage 75 and an outlet 76. Rod 54 includes a central passage 77 therein into which lubricant is admitted from chamber 72 through inlet 78, provided just below the plunger portion 91. Outlet passages 79 and 80 lead from the central passage 77; these can communicate with passage 73.

When the rod 54 is lowered, the plunger portion first cuts off the flow of lubricant from the reservoir 31 and from passage 73 through passage 74. Continued movement of rod 54 then compresses the lubricant in chamber 72, passage 77, outlet passages 79 and 80 and passage 73 so that the lubricant is applied forcefully to the die 14 as the bullet is forced therethrough. When the rod 54 is raised, the excess pressure is finally released into passages 74, 75 and 76 from the die and from passage 73. However, atmospheric release only occurs after plunger 54 has moved upwardly to open passage 74. The first release of any excess pressure in conduit 73 is into chamber 72 so that a minimum release of lubricant occurs to the atmosphere through outlet 76. This is possible because of the thick viscous nature of the lubricant employed.

From the foregoing, we believe it will be apparent that we have provided a novel and simple bullet sizer and lubricator which is effective to size and lubricate a bullet with an adequate and uniform quantity of lubricant. The only lubricant wasted is that released to relieve the pressure.

We claim:

1. A bullet-sizer and lubricator comprising a bullet-sizing die having a channel for lubricant passage to said die; a lubricant supply normally maintained under a first pressure to supply lubricant to said channel; a conduit connecting said lubricant supply to said channel; a supple-

mental lubricant pressure chamber; a lubricant pressure piston movable in said supplemental chamber to apply a second pressure in excess of said first pressure to lubricant in said channel; a valve in said conduit including a valve member movable between a valve open position wherein lubricant can flow through said conduit and a valve closed position wherein the valve member prevents the flow of lubricant through said conduit; a plunger for forcing a bullet through said die; a lever connected to said plunger, said valve member, and said pressure piston for moving said plunger, valve member and piston; said lever arm being movable in one direction simultaneously (1) to position a bullet inside of said die, move said valve member to said open position and move said pressure piston to supply a lubricant under said second pressure to a bullet in said die and in another direction simultaneously (2) to move said plunger away from a bullet in said die, move said valve member to a valve closed position and retract said pressure piston from its pressure application.

2. A bullet-sizer and lubricator comprising a bullet-sizing die having a lubricant supply channel therein; a plunger movable along the longitudinal axis of said die to force a bullet into and through said die; a lubricant conduit connected to said die lubricant supply channel; a valve member positioned parallel to said plunger and movable in a channel extending parallel to said die axis and across said lubricant conduit; said valve member having a transverse passage therein extending parallel to said conduit; a lubricant pressure cylinder connected to said conduit; means for supplying a lubricant at a first pressure to said cylinder; a piston in said cylinder movable to apply a second pressure to lubricant in said cylinder, said second pressure being in excess of said first pressure; a lever arm connecting said plunger, said valve member and said pressure piston; said lever arm being movable in one direction simultaneously (1) to position a bullet inside of said die, move said valve member to align said transverse passage in said member with said conduit and move said pressure piston to apply said second pressure to said lubricant to force lubricant to said bullet and in another direction simultaneously (2) to move said plunger away from said bullet in said die, move said valve member to transpose said transverse passage to a position out of alignment with said conduit and move said pressure piston to release the second pressure on said lubricant.

3. A bullet-sizer and lubricator comprising a bullet-sizing die having a lubricant supply channel therein, a plunger movable along the longitudinal axis of said die to force a bullet into and through said die; a cylinder extending parallel to said die axis; a combined valve-piston member mounted to move reciprocally in said cylinder and having a face thereon to apply pressure to a lubricant in said cylinder; a conduit extending between a first port in said cylinder and said lubricant channel; said valve-piston member including an interior passage extending from a second port on said piston face to a third port in a wall on the piston; a lubricant supply normally maintained under a first pressure to supply lubricant to said cylinder for compression to a second pressure through an inlet orifice in the side of said cylinder; a handle; a lever arm connecting said handle, said plunger and said valve piston member; said lever arm being mov-

able in a first direction simultaneously (1) to position a bullet inside of said die, move said valve piston member (a) to block said inlet orifice, (b) to align said third port with said first port in said cylinder and (c) to apply a second and increased pressure to lubricant confined between said piston compression surface and the walls of said cylinder; and movable in another direction simultaneously (2) to move said plunger away from the bullet in said die and move said valve piston member (a) to block said first port and (b) to open said inlet orifice to release the second pressure on said lubricant.

4. A bullet-sizer and lubricator comprising a bullet-sizing die having a lubricant supply channel therein; a plunger movable along the longitudinal axis of said die to force bullet into and through said die; a cylinder including a first portion thereof having a first diameter and a second portion thereof having a second and lesser diameter; said cylinder extending parallel to said die axis; a piston member mounted to move reciprocally in said cylinder; said piston member including a first portion having substantially the same diameter as said first cylinder portion diameter and a second portion having substantially the same diameter as the diameter of said second cylinder portion; a conduit extending between a first port in said first portion of said cylinder and said lubricant channel; said piston member including an interior passage extending from a second port in said second portion of said piston to a third port on the wall of said first portion of said piston; said second port being adjacent to the junction between said first and said second piston portions; a lubricant release duct extending between said lubricant channel and a fourth port in the wall of said second portion of said cylinder; a lubricant supply normally maintained under a first pressure to supply lubricant for compression to a second pressure through an inlet orifice in side of said first portion of said cylinder; a lever arm connected to said plunger and said piston member; said lever arm being movable in a first direction simultaneously (1) to position bullet inside of said die, move said piston member (a) to close said inlet orifice and said fourth port, (b) to align said third port with said first port and (c) to apply a second and increased pressure to lubricant confined in the space between one end of said first piston portion and one end of said first cylinder portion; and movable in another direction simultaneously (2) to move said plunger away from the bullet in said die and move said piston member (a) to close said first port and (b) to open said inlet orifice and said fourth port to release the second pressure on said lubricant.
